(No Model.)

N. M. BOWEN.

COMBINED FANNING MILL AND SEED CLEANER.

No. 296,309.

Patented Apr. 8, 1884.

Fig. 1.

UNITED STATES PATENT OFFICE.

NEWTON M. BOWEN, OF KNIGHTSTOWN, INDIANA.

COMBINED FANNING-MILL AND SEED-CLEANER.

SPECIFICATION forming part of Letters Patent No. 296,309, dated April 8, 1884.

Application filed November 10, 1883. (No model.)

To all whom it may concern:

Be it known that I, NEWTON M. BOWEN, of the town of Knightstown, county of Henry, and State of Indiana, have invented certain new and useful Improvements in a Combined Fanning-Mill and Seed-Cleaner, of which the following is a correct specification.

The object of my invention is to provide a fanning-mill and seed-cleaner combined with the necessary mechanism for more effectually separating mixed seed and grain and freeing the same from all foreign substances than can be effected by any of the fanning-mills and seed-cleaners now in use. I accomplish these objects by means of the devices described in the following specification.

By reference to the accompanying drawings, filed herewith and made a part of this specification, in which similar letters of reference relate to similar parts of my invention, Figure 1 is a longitudinal vertical section of my device, showing a fanning-mill with my improvements applied. Fig. 2 is a vertical cross-section of my device on the line $x x$ of Fig. 1, 25 with the wings of the fan broken off in order to show those parts of my invention which would be seen if looking from the front of the mill.

In Fig. 1, Ac' is an air-chamber formed by the partition p and the wall p' .

Ac^2 is the drum, in which the fan Fa revolves.

D is a damper, which is provided for closing the space forming the air-chamber Ac' , 35 and shutting off the current of air from this chamber when occasion requires.

Sh represents shutters the slats of which are pivoted to a frame attached to the sides of the mill between the air-chambers Ac^2 and the top shoe, Ts . Said shutters, being hinged to a rod provided with a handle, h , can be opened or closed by moving the handle up or down, and the current of air from the fan shut off, if desired, or permitted to pass through the top shoe, Ts , at will.

Rs is a slotted riddle-shoe, extending from the throat of my hopper H to the top of the riddles Ri , for conducting the grain from the hopper H to the said riddles. The bottom of this shoe Rs is made of a series of slats, which are pivoted at each end to the frame, which forms the sides of said shoe Rs , and hinged to

a rod or wire, h^2 , and can be opened or closed at will, just as the slats of an ordinary window-shutter are opened and closed. It will 55 be readily seen that when these slats are closed the bottom of my riddle-shoe Rs presents a smooth surface, over which the grain moves in its transit from the hopper H to the riddles Ri , and when opened, as shown in drawings, 60 form apertures in the bottom of my riddle-shoe through which the current of air from the fan Fa passes, the advantages of which are hereinafter set forth. This shoe Rs , thus constructed, I call a "slotted riddle-shoe," in order to distinguish it from the top and bottom shoes, Ts and Bs , when referring to it in this specification.

Fi , Fig. 1, represents whippers fixed upon a shaft, $f b$, pivoted to the frame of the mill, 70 and provided with shakers attached to the frame of the top shoe, Ts . The motion of the top shoe causes the whippers to move up and down and toss the straw and chaff violently, shaking all the grain out, permitting it to fall 75 on the riddles comparatively free from chaff and straw.

Bs is the bottom shoe of my fanning-mill, in which is placed four riddles, Dr , of any desired fineness, which are made to discharge 80 into boxes $b b' b^2 b^3$, placed immediately beneath the bottom shoe, Bs .

Cw is a crank-wheel, attached to the shaft upon which the fan Fa is fastened. This wheel, being connected with the crank-lever, mounted 85 on rod ro , by means of connecting-rod Cr^2 , imparts a reciprocating motion to the equalizing-lever el , rigidly attached to said rod. (See also Fig. 2.) This lever el , being attached to the top shoe, Ts , by means of the 90 connecting-rod b^4 , and to the bottom shoe by the connecting-rod b^5 , carries these shoes back and forth with every revolution of the crank-wheel Cw .

I prefer to attach the devices for shaking 95 my riddles to the center of the shoes, as shown in Fig. 2; but it will be readily seen that the same result may be accomplished by attaching the said devices for shaking my shoes Bs and Ts to the top of the top shoe and the bottom of the bottom shoe, as seen by the dotted lines in Figs. 1 and 2, (marked e and l'), actuated by crank-wheel Cw through the connecting-rods Cr and Cr' .

The method of operating my device is as follows: The hopper being filled with wheat containing much chaff and straw, I close the damper D and open the shutters *sh*, and also 5 the slots of the slotted riddle-shoe *Rs*, thus forcing the entire volume of air from the fan through the top shoe, *Ts*. By closing the shutters *sh* and the damper D and leaving the slots of the slotted riddle-shoe *Rs* open the 10 current of air passes through the slotted riddle-shoe and thence over the riddles, thereby materially increasing the feed of the chaff and grain. This is especially valuable in winnowing clover-seed or any grain containing much 15 chaff and straw, which has a tendency to choke the throat of all mills not provided with my device.

To prevent the straw and heads of wheat from choking up the riddles, I provide the 20 whippers *Fi*, which, being firmly attached to the bar *fb*, pivoted to the frame of the mill, as above described, tosses the straw and chaff up, which, being caught by the wind from the fan, is carried over the riddles, out of the mouth 25 of the mill, without coming in contact with the riddles.

To prevent the straw and chaff from choking the throat of the hopper, I close the shutters *Sh* and the damper D, leaving the slots of the 30 riddle-shoe open, the air from the fan *Fa*, in passing through the riddle-shoe, carries the straw and chaff away from the mouth of the hopper, thus clearing the throat of the hopper from those obstructions which in all ordinary fanning-mills retard the operation of the mill. To more effectually accomplish this 35 purpose, the feed-fingers *Sr* are attached to the riddle-shoe, and, moving with the top shoe, *Ts*, carry the chaff and straw forward with the forward motion of the shoe, while the wind 40 from the fan prevents the said straw and chaff from returning with the feed-fingers. This operation, being repeated at every revolution of the crank-wheel *Cw*, renders it impossible 45 for the throat of the hopper to become choked. Should the wheat contain much cheat, I close the shutters *Sh* and the slotted riddle-shoe *Rs* and open the damper D, thus transferring the current of air through the air-chamber *Ac'*, as 50 indicated by the dotted arrows, to the lower shoe, *Bs*. Said current of air, impinging against the inclined surface of the lower riddles, *Dr*, meets the descending grain as it falls from the top shoe onto the riddle of the lower shoe, and 55 since the cheat, timothy-seed, and cockle are lighter than the grains of wheat, they are car-

ried by the force of the wind far up on the riddle, and, falling on the screens, are sifted through in their respective drawers, as indicated by the drawings, Fig. 1.

60

The advantages I gain by employing my device are, first, by means of the whippers *Fi*, feed-fingers *Sr*, and slotted riddle-shoe *Rs*, in combination with the current of air from the fan *Fa*, any grain or clover-seed, no matter 65 how much chaff it may contain, passes freely through the throat of my hopper into the top shoe, *Ts*, when the straw and chaff are separated from the grain and blown out of the mouth of the mill without touching the riddles 70 and thus choking them up, as is usual in all ordinary fan-mills; second, with my crank-wheel *Cw*, connecting-rod *Cr*, crank-lever *Cl*, rod *ro*, and its equalizing-lever *el*, connected with the top and bottom shoes, *Ts* and *Bs*, I produce a rapid, smooth, and regular sifting motion for the shoes, which, combined with the current of air from the air-chamber *Ac'*, thoroughly separates the various seeds and grains that may be mingled with the wheat, depositing each in a receptacle to itself perfectly free from all grain or foreign substance that may vary from it either in size, shape, or weight. Thus I can convert what is usually termed 75 "seconds" into good merchantable wheat 80 weighing sixty pounds to the bushel, a feat which has never been accomplished by any mill heretofore invented.

75

Having thus fully described my invention, its purposes, and advantages, what I claim as 90 new, and desire to secure by Letters Patent, is—

1. In a fanning-mill and seed-cleaner combined, the air-chamber *Ac'*, formed by the partition *p* and the wall *p'*, and provided with 95 damper D, in combination with drum *Ac²*, shutters *sh*, fan *Fa*, top shoe, *Ts*, and bottom shoe, *Bs*, substantially in the manner and for the purpose set forth.

2. In a fanning-mill and seed-cleaner, the 100 combination of the top shoe, *Ts*, riddles *Ri*, slotted riddle-shoe *Rs*, whippers *Fi*, feed-fingers *Sr*, and mechanism for operating the same, substantially in the manner and for the purpose set forth.

105

In witness whereof I have hereunto set my hand and seal, at Indianapolis, Indiana, this 30th day of October, A. D. 1883.

NEWTON M. BOWEN. [L. S.]

In presence of—

H. J. EVERETT,
JOHN H. HARFORD.
